UNITED STATES PATENT OFFICE.

ALFRED W. BLENDOW, OF MAPLEWOOD, AND LOUIS H. BLENDERMANN, OF SOUTH ORANGE, NEW JERSEY, ASSIGNEES TO NATIONAL GUM COMPANY, INC., OF NEWARK, NEW JERSEY, A CORPORATION OF NEW JERSEY.

PASTRY CUTTER.

Application filed July 10, 1926. Serial No. 121,625.

This invention relates to machines for cutting sheets of plastic material into uniform fragments.

It is one object of the invention to provide a machine capable of shearing sheets of chewing gum, confectionery, dough, etc., rolled to a uniform thickness into lozenges or diamonds of true and uniform rhomboidal shape.

10 A further feature is in the provision of means whereby such lozenges are formed with a double bevel on each of their several edges during the process of their manufacture and clean cut so that no ragged or 15 rough surfaces appear.

Another aim is in the production of a machine for accomplishing such purposes in the quantity production of goods, that is extremely simple and efficient and under 20 the instant control of an operator.

These and other minor objects are attained by the novel construction and combination of parts hereinafter described and shown in the accompanying drawings, forming a material part of this disclosure, and in 25 which:—

Figure 1 is a top plan view of an embodiment of the invention illustrating its application.

30 Figure 2 is a transverse sectional view taken on line 2—2 of Figure 1.

Figure 3 is a sectional view taken on line 3—3 of Figure 2.

Figure 4 is a rear end view of Figure 2.

35 Figure 5 is a fragmentary transverse sectional view taken through the oblique cutting rolls.

Figure 6 is a fragmentary plan view of the dough sheet as it leaves the machine.

40 Figure 7 is an enlarged perspective view of one of the completed products.

The machine comprises a hollow bed frame 10 of rectangular profile, its longitudinal members having flanges 11 and 12, 45 respectively at the front and rear, the latter being provided with an extension 13 at its forward end and on the front side is an

open frame extension 14 these members to be supported by a bench or legs not shown.

Supported by the main bed 10 are a plurality of channel shaped spacers 15 carrying a flat level platform 16 of considerable area, having at its rear edge a raised longitudinal rail 17 adapted to guide a sheet 18 of plastic material to be cut, this material having been rolled to a uniform thickness by means well known in the trade.

Bolted to the bed flanges 11 and 12 are a pair of double pillow blocks 19, a similar pair of pillow blocks 20 being fixed on the flange 11 and extension 13, in the same horizontal plane but at an oblique angle to the first blocks.

Each pillow block carries two bearings 21, 21' and 22, 22' respectively upper and lower, the lower being seated in the bottoms of the blocks and the upper supported by coiled compression springs 23 disposed between the bearings, which are slidably mounted and adjusted by screws 24 in the pillow block caps 25.

Revolutely mounted in the upper rear bearings 21 is a shaft 26, a similar shaft 27 being in the lower bearings, these shafts extending at right angles across the bed.

Another pair of shafts 28 are mounted in the bearings 21 of the forward angularly disposed blocks 20 as seen in Figure 1, oblique to the other shafts.

Fixed on the shafts 26 and 27 are sleeves 29 and disposed on the sleeves are flat circular discs 30 having bevelled edges, these discs being held in rigid uniform spaced relation by spacing collars 31, the lower cutting discs extending through appropriate slotted openings 32 in the platform 16 to meet the peripheries of the upper discs in the manner of pairs of circular shears.

Fixed on the forward, angular shafts 28 are similar sleeves 33 carrying a series of longitudinal segments 34, having between their adjacent faces a series of straight, full length knives 35 provided with extending bevelled edges arranged in meeting relation,

at the center of the thickness of the sheet, the lower set of knives operating in a groove 36 in the platform 16.

This arrangement is best seen in Figure 5 and it will be noted that the peripheral surfaces of both series of segments 34 make contact with the material 18, as the shafts are revolved, tending to retain the sheet level and preventing its displacement by 10 action of the cutters 35, which are timed to rotate in proper relation with advancement of the sheet.

It will also be noted that the bevelled edges of the cutters 30 produce bevelled slits 18', 15 as seen in Figure 3, while the bevelled edges of the knives 35, extending transversely across the slit sheet, produce correspondingly bevelled edges 18'', as seen in Figure 5.

Fixed on the outer ends of the shafts 26 20 and 27 are spur gears 37 and 38 and the shafts 28 of the forward cutters are similarly connected by spur gears 39.

Secured on the front end of the shaft 27 is a gear 40 and another like gear 41 is on 25 the corresponding end of the lower angular shaft 28, both gears 40 and 41 being driven by an intermediate pinion 42 fixed on a shaft 43 mounted in bearings 44 carried on the front extension 14 of the bed frame.

30 A pulley 45, driven by a belt 46, is rotatably mounted on the shaft 43 which can be driven by it upon engagement of a sliding friction clutch member 46.

The clutch is actuated by a handled lever 35 47 extending conveniently for an operator and pivoted to a bracket 48 carried by the rear member of the extension 14.

The operation of the machine is believed 40 clearly apparent from the foregoing, taken in connection with the drawings and it will be obvious that a sheet of suitable material may be cut to produce a multiplicity of parts, as seen in Figure 6, which upon separation will appear as in Figure 7, the angularity of each individual tablet being in conformity with the angular relation of the front and rear cutter carrying rolls.

The foregoing disclosure is to be regarded 50 as descriptive and illustrative only, and not as restrictive or limitative of the invention, of which obviously an embodiment may be constructed including many modifications without departing from the general scope herein indicated and denoted in the appended 55 claims.

Having thus described our invention, what we claim as new and desire to secure by Letters Patent, is:—

1. A machine for cutting a plastic sheet 60 into uniform rhomboidal tablets, comprising a platform over which the sheet is moved, a series of slitting cutters arranged above and below said platform the edges of said cutters meeting in a plane midway the thickness of the sheet, the axes of said cutters be-

ing at right angles to the path of the sheet, a second series of cutters disposed in the same horizontal planes as the first cutters and at an oblique angle thereto, and means for rotating all of said cutters simultaneously. 70

2. A machine for cutting a plastic sheet into uniform rhomboidal tablets, comprising a platform over which the sheet is moved, a plurality of circular shears having bevelled edges meeting in a plane midway the thickness of the sheet and operable in the direction of its advancement, a plurality of roll carried knives having bevelled edges, meeting in the same plane above and below the 80 sheet, the axes of the rolls being at an angle with the axes of said shears, and means for driving said shears and knives simultaneously. 75

3. In a machine of the class described, the 85 combination with a bed, and a platform mounted thereover, of two pairs of bearings on said bed at the sides of said platform, shafts in said bearings above and below the platform, one pair of said shafts being at 90 right angles to the platform and the other pair at an oblique angle thereto, cutters on all of said shafts, said cutters having bevelled edges meeting in a plane at the center of a sheet of material on said platform 95 whereby the portions cut therefrom are given bevelled edges, and means for rotating said shafts simultaneously. 100

4. In a machine of the class described, the 105 combination with a bed and a platform mounted thereover, of a pair of shafts carried in bearings respectively above and below the platform at a right angle thereto, disc cutters on said shafts meeting in a plane above the platform, a second pair of shafts arranged transversely at acute angles to the first named shafts, spaced longitudinal cutters on said second shafts meeting in a horizontal plane equivalent to the plane of the circular cutters, geared connections between each pair of shafts, and a single driving means for all of said shafts. 110

5. In a machine of the class described, the 115 combination with a platform adapted to receive a sheet of plastic material to be moved therealong, of means for shearing said sheet into strips of uniform width, other means arranged transversely at acute angles to the first named means for shearing the strips transversely to produce diamond shaped tablets, and means cooperative with the shearing means to form double bevelled edges in each tablet. 120

6. In a machine of the class described, the 125 combination with a platform adapted to receive a sheet of plastic material to be moved therealong, of a pair of shafts having bevelled cutter discs to meet at the median line of thickness of the sheet, ring spacers between said discs, the peripheries of said 130

spacers to make contact with the opposite sides of the sheet, a second pair of shafts having bevelled edged longitudinal blades to meet in the center of thickness of the sheet, segmental spacers between said blades, the peripheral surfaces of said segmental spacers to make contact with opposite sides of the sheet, the axes of the first pair of

shafts being at an acute angle with the axes of the second named shafts, and means for driving all of said shafts in unison.

This specification signed this ninth day of July, 1926.

ALFRED W. BLENDOW.
LOUIS H. BLENDERMANN.
